HAND COVERING

Olof Hagström, Gamlakarleby, Finland

Application December 5, 1947, Serial No. 789,796
In Finland December 7, 1943

5 Claims. (Cl. 2—169)

1

In heretofore known hand coverings intended for hard usage and in the main consisting of two parts, back piece and front piece or palm having a thumb element attached thereto, an undesired crease in the bent section between the thumb element and palm is formed on usage. Moreover a seam is also located here. At work the crease formation is a source of inconvenience and annoyance and inevitably results in the fact that said hand covering wears out along said crease thus rendering it unfit for use as a patch on this place is impractical.

The object of this invention is the provision of a hand covering of the class described in which there are none of the defects stated above. This is accomplished by cutting out the different pieces of the hand covering in a specific manner.

Referring to the accompanying drawings:

Fig. 1 is a view of a blank for both the front and back pieces of the hand covering in accordance with the preferred form of the invention;

Fig. 2 is a view of the thumb trunk in accordance with the Fig. 1 form;

Fig. 3 is a view of a blank for a gusset in accordance with the Fig. 1 form;

Fig. 3a is a similar view of a slightly modified form of gusset;

Fig. 4 is a side view of an assembled hand covering incorporating the blanks of Figs. 1-3;

Fig. 5 is a view of a blank for a back piece of a modified form of hand covering;

Fig. 6 is a view of a blank for the front piece of said modified form;

Fig. 7 is a view of a blank of a gusset for said modified form;

Fig. 8 is a view of a blank of a thumb trunk for said modified form;

Fig. 9 is a side view of an assembled hand covering incorporating the blanks of Figs. 5-8;

Fig. 10 is a view of a blank for the back piece of another modified form of hand covering;

Fig. 11 is a view of a blank for the front piece of said other modified form;

Fig. 12 is a view of a blank of a gusset for said other modified form;

Fig. 13 is a view of a blank of a thumb trunk for said other modified form;

Fig. 14 is a view of a blank of the other gusset for said other modified form and

Fig. 15 is a side view of an assembled hand covering incorporating the blanks of Fig. 10-14.

Referring in detail to the embodiment of Figs. 1-4 the back piece 1 and the front or palm piece 2 of the hand covering are shown in blank form

5 in Fig. 1 in side by side relationship ready for folding into operative position. The piece 2 carries a lower protruding piece 3 to form the grip side of the thumb. It is apparent that the front piece 2 will substantially overlie the back piece 1 save for a lower portion of the latter. The thumb trunk piece 4 however carries a lower horizontally extending portion which is joined to the front piece and closes the gap opposite the lower portion of the back piece. The upwardly extending portion of the piece 4 forms the thumb trunk proper.

The hand covering is completed by the wedge shaped gusset 5 shown in Fig. 3. This gusset is 15 concavely curved along its upper edge 6 on a radius suitable for enabling an effective grip between the thumb portion and palm portion of the particular sized hand covering. Obviously this radius will vary in accordance with the size 20 of the hand covering while retaining the same center.

The assembled hand covering as illustrated in Fig. 4 is formed by overlying the front piece 2 over the back piece 1 in opposition to each other 25 and joining their free side edge portions. The thumb trunk piece 4 has its upper right hand edge portion as viewed in Fig. 2 secured to the mated lower edge portion of the front piece. The gusset 5 is secured in place as shown in Fig. 30 4 with its inclined side portions secured to the related portions of the thumb trunk and back piece and with its curved upper edge portion 6 secured to the opposed edge portion of the front piece.

This construction totally eliminates the formation of a crease in the bent portion of the hand covering between the thumb and the palm even when a gripping position is taken as illustrated in Fig. 4.

If desired the sides of the gusset 5 may be 40 curved a little towards the edge portion 6 as shown in Fig. 3a, rather than being straight. This imparts a grip like curve to the whole of the hand covering.

The other two embodiments correspond in the main to the one hereinabove described with the exception that herein the length of the front piece or palm is equivalent to that of the back piece. Thus the seam across the front piece or 45 palm is avoided. The gussets 9 (Fig. 7) and 16 (Fig. 12) differ from gusset 5 in that the curved upper base line is lengthened and extends to the top of the finger, according to Fig. 5-9 and almost to the top of the finger according to Figs. 55 10-15.

According to Figs. 5-9 the gusset 9 is joined to back piece 13 along the edge portion 8 and to the front piece 11 along the curved edge portion 7, which thus falls along the edge portion 10 between the finger top and the protruding part 12. The edge portions 7 and 10 are both curved in the same manner corresponding to the normal grip of the hand. The third edge portion 14 is joined to the thumb trunk 15 and is also slightly curved.

According to Figs. 10-15 the gusset 16 is joined to the front piece 21, the back piece 22 and the thumb trunk 24. The edge portions 17 and 19 are stitched together and both are curved correspondingly to the normal grip of the hand. The curved edge portion 18 is joined to the edge portion 25 of the back piece 22. The third side 26 of the piece 16 is joined to the thumb trunk 24. On the opposite side of the gusset 16 is another gusset 28, which with its curved edge portions 27 and 29 is stitched to the edge portion 30 of the front piece 21 and the edge portion 23 of the back piece 22.

The ready-stitched hand coverings according to these embodiments are still more "grip-like" than the one in Fig. 4, as evident from Figs. 9 and 15.

According to the embodiments illustrated in Figs. 5-9 and Figs. 10-15 the edge portions of the gussets 9 and 16 which engage the mated edge portions of the respective thumb trunks 15 and 24 can be either straight or slightly curved toward the edge portions to be joined to the front piece.

In the illustrated embodiments the pieces 5, 9 and 16 have been designed as a separate piece, which is of advantage in the respect that small bits of leather such as remnants and the like can be utilized, which involves noteworthy saving of expensive raw material.

The separate pieces of the glove are joined together in the usual way either with or without the use of protecting leather tape or strip in the seams.

Having thus described my invention what I claim is:

1. A hand covering comprising a back piece, a thumb trunk formed with a lower transverse portion and a portion extending upwardly therefrom, a front piece formed with a main portion, and with an upwardly extending portion corresponding to said upwardly extending portion of said thumb trunk, and a gusset, said gusset being formed with a plurality of edge portions one of said edge portions being joined to the edge portion of said back piece at the thumb side thereof, another of said edge portions being joined to the adjacent edge portion of said transverse portion of said thumb trunk and a third of said edge portions being joined to the edge portion of said front piece extending between said upwardly extending portion thereof and said main portion thereof, the line of joinder of said third edge portion with said edge portion of said front piece being concavely curved to provide a normal handgripping curve between the thumb part and body part of said hand covering.

2. A hand covering as in claim 1 wherein said third edge portion of said gusset is the upper edge portion thereof and is concavely curved downward on a short radius.

3. A hand covering comprising a back piece and a front piece, said front piece including a main portion and an upwardly extending portion extending away from said main portion, said back

piece and said main portion of said front piece being formed to receive the fingers of a hand therebetween and said upwardly extending portion being formed to overlie the inner side of the thumb of the hand, a thumb trunk including a lower wide portion and an upwardly extending reduced portion formed to overlie the outer side of the thumb of the hand, said back piece, front piece and thumb trunk presenting joining edge portions at the thumb side of said hand covering, and a gusset formed with side edge portions and an upper edge portion for engagement with said joining edge portions of said back piece, front piece and thumb trunk, said respective edge portions being joined together and said upper edge portion of said upwardly extending portion of said thumb trunk being joined to the adjacent edge portion of said front piece extending from the main portion thereof towards said upwardly extending portion thereof, the line of joinder of said upper edge portion of said thumb trunk and said extending edge portion of said front piece being concavely curved downward on a short radius.

4. A hand covering comprising a back piece, a thumb trunk including a lower wide portion and a reduced upwardly extending portion, a front piece including a main part to overlie said back piece and form with the same a finger receiving portion of said hand covering, a protruding part extending away from said main part and corresponding to said reduced upwardly extending portion of said thumb trunk and lying opposite to said upwardly extending portion of said thumb trunk to form with the same a thumb receiving portion of said hand covering and a joining portion extending between said main part and said protruding part, a substantially wedge shaped gusset formed with downwardly and inwardly extending side edge portions and with a top edge portion curved concavely downwardly on a short radius, said gusset being located at the thumb side of said hand covering and having its edge portions joined to the respective joining edge portions of said back piece, front piece and thumb trunk at said thumb side of said hand covering, said concavely curved edge portion of said gusset being secured to the adjacent edge portion of said joining portion of said front piece, said edge portion of said joining portion being curved in correspondence with said concavely curved edge portion to form a concavely curved joining section between said finger receiving portion and said thumb receiving portion of the hand covering.

5. A hand covering as in claim 4 wherein said downwardly and inwardly extending side edge portions of said gusset are slightly curved toward said top edge portion thereof.

OLOF HAGSTRÖM.
